E. F. LACY AND D. K. WOODBURY, OF DANVILLE, ILLINOIS.

Letters Patent No. 77,625, dated May 5, 1868.

IMPROVEMENT IN HAMES.

The Schedule referred to in these Letters Patent and making part of the same.

TO ALL WHOM IT MAY CONCERN:

Be it known that we, E. F. LACY and D. K. WOODBURY, of Danville, in the county of Vermillion, and in the State of Illinois, have invented certain new and useful Improvements in Hames; and do hereby declare that the following is a full, clear, and exact description thereof, reference being had to the accompanying drawings, and the letters of reference marked thereon.

In the annexed drawings, making a part of this specification, A represents the lower part of a hames made of wood, and in the form shown, so as to correspond with the form and shape of a horse-collar, and fit thereon. The part A is provided with the usual strip, or plate and loop, at its lower extremity, and with hold-back rings, as is fully shown. The corners of the outside of the piece A are cut away, as is shown, leaving a shoulder or tongue on its outside. The plate for securing the loop at the lower end is screwed to the piece A, and extends up the whole length of said piece and bent over the ends thereof. The upper part of the plate, as shown at B, from the beginning of the tongue of the piece A, is made a little narrower than the thickness of the piece A.

C represents a metallic sliding plate, made slightly curved, so as to correspond with the upper end of a collar, and made adjustable at any desired point by means of the screw-loop D, which passes through one of a series of holes therein into the plate B and wood piece A. The plate C is provided with or has fitted to it the ordinary loop for fastening the top of the hames, and is provided with lips, x x, which fit and work over the metallic strip or plate, and thereby hold the said plate firmly in place.

The lips x x slide in grooves made by the plate B and shoulders and tongue of the piece A, and the plate B slides in grooves made by or between the plate C and its lips x x.

By means of the adjustable or sliding plate C, this hames may readily be altered to correspond with or fit a collar of any size required.

Having thus fully described our invention, what we claim as new, and desire to secure by Letters Patent, is—

The adjustable metallic plate C, provided with L-shaped ears, x x, which project beyond and under the stationary plate B, and work in vertical grooves in the wooden hames A, all constructed, arranged, and operating as set forth.

In testimony that we claim the foregoing, we have hereunto set our hands, this 3d day of February, 1868.

E. F. LACY,
D. K. WOODBURY.
